CLAIM

The ornamental design for a salad bowl, as shown and described.

DESCRIPTION

FIG. 1 is a front elevational view of a salad bowl, showing my new design, the right, left and rear views being a mirror image;

FIG. 2 is a top plan view thereof;

FIG. 3 is a bottom plan view thereof; and

FIG. 4 is a top and right side perspective view thereof. In each of FIGS. 1, 3 and 4 only a fragmentary portion of pattern on the salad bowl is shown, it being understood that the pattern extends continuously about the walled circumference thereof.
